UNITED STATES PATENT OFFICE.

PATRICK A. TOOMEY, OF CHICAGO, ILLINOIS.

MACHINE FOR CASTING STEREOTYPE PRINTING-PLATES.

1,309,309.

Specification of Letters Patent.

Patented July 8, 1919.

Application filed June 25, 1917. Serial No. 176,650.

To all whom it may concern:

Be it known that I, PATRICK A. TOOMEY, a citizen of the United States, residing at Chicago, in the county of Cook and State of Illinois, have invented new and useful Improvements in Machines for Casting Stereotype Printing-Plates, of which the following is a specification.

This invention relates to an apparatus or machine for casting type high stereotype printing plates from a matrix or mat.

Among the objects of my invention is to improve the construction of a casting machine of the type referred to, in the several particulars as will hereinafter more fully appear, and to provide in particular improvements in the casting or mold box of such an apparatus, so that type-high printing plates of various widths and lengths may be readily cast, ready for use without undergoing the usual trimming operations, except sawing off the ends where the metal is poured.

A further object of my invention is to arrange the melting pot above the casting box, so that the molten stereotype metal may be allowed to flow into the mold cavity by gravity, and thus avoid the necessity of using a dipper, or raising and tilting a melting pot.

Another object of my invention is to provide a manually operable valve member for controlling the gravity flow from said melting pot, and further to so arrange and construct the valve member that the latter may be rotated or turned against its seat for the purpose of grinding or removing therefrom any particles of foreign matter, which if allowed to remain lodged on the valve seat would hinder the valve member from tightly and properly closing against its seat.

A further object of my invention is to provide the frame, employed for clamping the matrix or mat in the mold cavity, with means serving to compensate for the shrinkage of the metal around the edge of the printing plate being cast and thereby prevent the type characters immediately adjacent such edges from being entirely eliminated or being distorted or warped by such shrinkage.

Another object of my invention is to provide means for cutting off a greater portion of the poured end of the metal during the

casting of the printing plate, so that when the latter has solidified and been removed from the mold box, the poured end of the plate will be partly severed, thus making it necessary to saw or cut through but a small amount of said poured end.

And another object of my invention is to provide a core carrying plate having detachable connection with one of the mold members, so that either a solid or cored type-high printing plate may be cast to meet the conditions required; a solid plate for one having a bastard measure, and a cord plate for one having a standard newspaper or like measure.

The invention consists further in the matters hereinafter described and more particularly pointed out in the appended claims.

In the accompanying drawings—

Figure 1 is a perspective view of a casting machine or apparatus constructed in accordance with my invention, the two-part mold or casting box thereof being shown in its fully opened position;

Fig. 2 is a top plan view, with some parts broken away and some in section, of the machine as shown in Fig. 1, with the exception that the matrix clamping frame is shown in lowered position resting on the flat bed of the movable mold member;

Fig. 3 is a fragmentary vertical sectional view taken through the parts illustrated in Fig. 1, with the exception that the two-part mold box is shown in its fully closed position, and the cut off slug and its attached rod are shown in the position they would occupy when in use;

Fig. 4 is a horizontal sectional view taken on line 4—4 of Fig. 3;

Fig. 5 is a sectional view of a detail of construction and taken on line 5—5 of Fig. 2; the mold box, however, being shown in closed position;

Fig. 6 is a vertical sectional view taken through the melting pot and showing the discharge valve structure thereof;

Fig. 7 is a sectional view of a detail of construction and taken on line 7—7 of Fig. 2;

Fig. 8 is a perspective view of a type-high stereotype printing plate cast by my machine, and showing the cut off slug and its attached rod before being withdrawn from the metal of the plate;

Fig. 9 is a perspective view of the same parts, and showing the rod referred to withdrawn from the metal of the plate;

Fig. 10 is a perspective view of the same parts, and showing both the slug and rod removed from the metal plate;

Fig. 11 is an enlarged sectional view taken on line 11—11 of Fig. 2 and showing how the metal of the printing plate being cast fills the inset or groove in one of the clamping bars, when the matrix or mat being used is devoid of a bolster;

Figs. 12 and 13 are like views, showing how the metal of the plate being cast fills the mold cavity adjacent the clamping bar, when the mat or matrix being used is provided with a bolster extending into the inset or groove of said bar;

Fig. 14 is a perspective view of the core-plate removed from the mold box of my machine;

Fig. 15 is a front elevational view showing the mold box fully open and illustrating the core-plate applied against the front face of the stationary mold member;

Fig. 16 is an enlarged horizontal sectional view, taken on line 16—16 of Fig. 15; and

Fig. 17 is an enlarged vertical sectional view taken on line 17—17 of Fig. 15.

Referring to the drawings, illustrating in detail one preferred form of type-plate casting machine embodying the features of my invention, 20 indicates the two-part mold or casting box thereof, and, as shown, said casting box comprises a stationary mold member 21 and a movable mold member 22, the latter being swung toward and from the stationary mold member in the opening and closing of said mold box. When the casting box 20 is closed, as shown in Fig. 3, the two mold members 21, 22 are clamped together by clamping members 23, 23, to be hereinafter more fully described. Said casting box 20 is provided with a mouth opening into the mold cavity formed between the mold members 21, 22 when the casting box is closed and into which cavity the molten stereotype metal is poured in the casting of a type-high printing plate from a matrix or mat previously inserted in said cavity. As shown, the stationary mold member 21 is mounted in an upright or vertical position on a supporting base or stand 24 and secured thereto by clamp bolts 25, 25. The stand 24 is preferably made in the form shown and extends forward of the stationary mold member, so as to provide a rest or support for the movable member 22 when the latter is swung downward into fully open position (Fig. 1). Said movable mold member 22 is pivoted or hinged at its inner or lower margin to said stand 24 by pivot pins 26, 26, so that said movable mold member may be raised and lowered in the opening and closing of the casting box. In Figs.

1 and 2, the casting box 20 is shown open, that is, the movable mold member 22 has been swung down into its lowermost or horizontal position and rests on the stand. To close the casting box, the movable member 20 is raised or swung upward against the stationary mold member and clamped thereto by the clamping members 23, 23. The two mold members 21, 22 are preferably rectangular in shape and are made the same size. The opposed faces of said mold members are made smooth and flat and form the front and rear walls of the mold cavity when the casting box is closed. Each of said mold members 21, 22 is strengthened by longitudinal webs 27 and transverse webs 28, made integral with the rear or exterior face thereof, as shown in Figs. 1, 2, 3, and 4.

Interposed between said mold members 21, 22 is an open, rectangular clamping frame 29, comprising connected side bars 30, 31 and end bars 32, 33, as best shown in Figs. 1 and 2. The side bars 30, 31 extend one along each side of the casting box and between the two mold members 21, 22 thereof, when closed together. The inner ends of the side bars 30, 31 are adjacent the inner or pivoted end of the movable mold member 22. The end bar 32 extends across the inner flat face of the movable mold member 22, and is connected with said side bars adjacent the inner ends thereof. Said frame 29 is pivoted or hinged at its inner end to the hinged end of the movable mold member, so that the frame may be swung upward from such mold member, when the latter is in its horizontal or open position. The outer or free ends of the side bars 30, 31 project beyond the outer edge of the movable mold member, and the other end bar 33 extends between and is secured to such portions of said side bars, thereby enabling said end bar 33 to extend across the movable mold member beyond the outer end thereof, and, furthermore, permit the remaining three bars of the frame to contact flatwise throughout their lengths against the opposed flat faces of said mold members. As shown in the drawings, the frame 29 is hinged to the movable mold member 22 in the following manner. The inner end bar 32 is spaced inwardly from the hinged edge of said movable mold member to provide a space into which project lugs 34, 34, made integral with said movable mold member (Figs. 1 and 2). The side bars 30, 31 are pivoted to said lugs by a rod 35. The bars 30, 31, and 32 are square in cross-section and all of the same height, and are clamped between the mold members 21, 22 when the casting box is closed, as shown in Figs. 3 and 4. Moreover, when the casting box is closed, said bars 30, 31, and 32 form the side and bottom walls of the mold cavity. The outer bar 33 is secured to the under side of

the side bars, so as to be out of endwise alignment therewith and provide a mouth or opening into the mold cavity along the entire upper edge thereof. Said outer bar 33 is provided between its ends with an elongated slot 36, the purpose of which will presently appear.

The movable mold member 22 is provided at its forward end with a pair of handles 37, 37, adapted to be grasped in the raising and lowering of said mold member. The stand 24 is provided at each side thereof with a portion 38 extending rearward of the stationary mold member 21. Said parts 38 also extend upward along each side of said stationary member, and are secured thereto by said bolts 25. Arranged above the casting box 20 is a melting pot 39, of the gravity feed type, and provided with a discharge spout 40, the lower end of which terminates just below the upper edge of the mouth of the mold cavity formed between the mold chambers when the latter are clamped together. Said spout 40 is provided with a vertical discharge passage 41, the upper end of which opens into the bottom of the pot 39 through a discharge port 42 (Fig. 6). Said port 42 is opened and closed by a vertically movable valve member 43, the latter being in the form of a rod, which extends above the top of said pot through a plug 44 closing the upper end of the chamber 45, in which the valve member is located. For raising and lowering said valve member 43, I provide a handle 46, which, as shown, is in the form of a lever arranged above the melting pot. Said handle 46 is pivoted at one end by a pivot pin 47 to a standard 48, rigidly secured to the side wall of the melting pot and extending upwardly above the same. The valve rod 43 extends upward and loosely through the handle 46, and is provided above the same with a hand piece 49, whereby the valve member 43 may be turned or rotated for grinding its conical end against its seat, for the purpose of removing any foreign particles that would obstruct the proper closing of the valve member on its seat. The valve member 43 is provided, on each side of the handle 46, with a fixed stop-member or washer 50, thereby enabling the valve member to be raised and lowered by said handle. The stereotype metal, from which the type plates are cast, is placed, in solid form, in the melting pot 39, the valve member 43 at such time being in closed position. Said solid metal is then converted into a molten mass by heat applied beneath the bottom of the pot. Any suitable form of heating means may be employed for such purpose, but in Fig. 3 I have shown a conventional form of gas or oil burner 51, located beneath the bottom of the pot. To maintain the heat around the side walls of the pot during the melting of the stereotype

metal therein, I surround the side walls of the pot with a heat-retaining sheet metal casing or housing 52, the upper end of which is closed by a top wall, as shown in Figs. 3 and 6.

Each clamp member 23 has the hook-shaped form shown in the drawings, and has one end located above a lug 53 projecting rearwardly from the side wall of the stationary mold member 21, as best shown in Fig. 3. Such end of the clamp member is pivoted to its associated lug by a vertically arranged pivot pin 54. The forward or free end portion 55 (Figs. 2 and 4) of the clamp is arranged at right angles to the body of the same, and, when the clamp is swung into a position extending around the sides of the closed mold members 21, 22, said portion 55 extends around, but is spaced outwardly from the back or exterior face of the movable mold member 22. A clamp screw 56 is threaded through the end portion 55, and has its inner end forced against the back of the movable mold member in clamping the two parts of the casting box together. As shown in Figs. 1 and 3, there are a plurality of such clamping members 23 vertically arranged at each side of the casting box, and all are pivotally connected, in the manner described, with the back of the stationary mold member 21. The inner ends of the clamp screws 56 are forced against that portion of the back of the movable mold member formed at the junction of the side and cross webs 27, 28. The inner or pivoted end of each clamping member 23, when in clamping position, bears or abuts against the associate side web 27, so that the pivot pin 54 is relieved of the pressure exerted on the clamp when the clamping screw 56 is forced against the movable mold member.

With the clamping frame 29, I employ an adjustable clamping bar 57, which is arranged to extend substantially parallel with the side bars of the frame and endwise between the end bars thereof, as clearly shown in Figs. 1 and 2. Said adjustable bar 57 has the same cross-sectional dimensions as each of the side bars 30, 31 of the frame, and is therefore type-high in thickness. The inner end of said bar 57 is square, and abuts endwise against the end bar 32, and its outer end terminates short of the slotted bar 33, as shown in Figs. 1 and 2. Said adjustable bar 57 is connected at its outer end with said slotted bar 33 by means permitting said bar 57, the set screws 58, 62, and 65 are first rearly and to be clamped in any of its positions of adjustment. Such means comprises a set screw 58, which is threaded into the forward end of said bar 57, and projects outward beyond and in endwise alignment with the same. Said set screw 58 is provided between its ends with two spaced but fixed collars 59, 59, between which is located

the head 60 of a screw-threaded stem 61. (See Fig. 5.) Said stem 61 is arranged at right angles to said set screw 58, and projects downward through the slot 36 in said bar 33, as clearly shown in Fig. 5. A milled thumb piece 62 has screw-threaded connection with said stem 61, and is designed to be forced against the under side of said slotted bar 33. At the inner end of and connected with the adjustable bar 57 is a rod 63, which extends laterally therefrom toward and loosely through and beyond the side bar 31. Said rod 63 also extends outward through a bearing block 64 secured to said side bar 31. A set screw 65 is employed for clamping said rod in any position of its longitudinal adjustment. The side bar 30, as well as the end bar 32, is provided along its inner lower edge with a rabbit, groove, or inset 66, and the adjustable bar 57 is provided with a like groove or inset along that lower edge opposite the grooved edge of the side bar 30. (See Figs. 3, 4, 11, 12, and 13.)

The casting machine described and shown is operated as follows: The mold box 20 may be made of such dimensions as to permit the casting at one operation of a one-piece type-high printing plate of a width and length for printing a full page of a daily newspaper or the like. The casting box 20 is first opened and the movable mold member 22 swung downward into horizontal position on the supporting stand 24. In such position of the parts, the clamping frame 29 rests upon the flat bed of the now open movable mold member. For casting a printing plate of the full dimensions of the mold box, the set screws 62 and 65 are loosened, and the adjustable bar 57 is moved laterally into position against the right-hand side bar 31. Said set screws are then tightened to clamp said bar 57 in such position, but before said bar 57 is clamped against lateral movement, the set screw 58 is turned so as to effect the forcing of the inner squared end of said bar 57 tightly against the inner end bar 32, and thus forms a tight joint between such parts, so as to prevent the molten metal, when poured into the mold cavity, from entering between such parts. The clamping frame 29 is then raised or swung upward above the flat bed of the movable member, and a paper matrix or mat, previously prepared and of a size for the printing plate to be cast, is placed flatwise upon the bed of the movable mold member, with the impressions of the type characters or other outlines to be cast facing in the required direction. Said mat is so placed that its side and rear marginal portions will be in position to be engaged and overlapped by the side and rear bars 30, 32 and the adjustable bar 57 when the clamping frame is swung downward thereagainst. In some instances the mat (67 as

shown in Figs. 12 and 13) is provided around the boundary of its casting face with an upwardly bulged portion forming a bolster 68, adapted to be received in the inset or groove 66 formed in the clamping bars 70 of the frame 29. After the mat has been placed on the bed of the movable member and clamped thereagainst by the clamping frame 29, the movable mold member 22 is raised or swung upward against the stationary mold member, carrying the mat and clamping frame therewith. The two mold members are then clamped tightly together by the clamps 23, 23, whereupon the molten stereotype metal is allowed to flow from the pot 39 into the mold cavity formed between said mold members. The molten metal is allowed to flow until the mold cavity is filled above the upper edge of the mat. The bars 30 and 57 form the side walls of the mold cavity, while the rear bar 32 forms the bottom wall thereof, and as such bars are type-high, the depth of the mold cavity is type-high, thus permitting a type-high printing plate to be cast. Consequently, the printing plate when cast does not require trimming to reduce its thickness or padding placed beneath the same when set in the press for printing. The bolsters 68 of the mat being received in the grooves 66 cause the side and rear edges of the printing plate cast to be below the printing surface of the plate, and further cause a straight edge to be formed, thus avoiding the necessity of trimming such edges of the plate before being placed on the press for printing. After the molten stereotype metal has solidified in the mold chamber, the casting box 20 is opened, and the cast printing plate removed. The next step is to saw or cut off the poured end of the plate, and then the latter is ready for insertion in the press. To cast another printing plate from the same matrix or mat, the casting operation described above is repeated. Should it be desired to use a different mat, but of the same size as the previous one used, the latter is substituted in place of the previous one and the method above described repeated.

To cast a type-high printing plate of a width and length of a standard newspaper column, or a printing plate of a width of two columns or more, but less than the full width of the mold box 20, or a printing plate having a bastard measure, as for instance a plate being two columns and one-half wide and of a length less than a standard column, I employ the adjustable clamping bar 57 in the following manner: After the casting box 20 is opened and the movable mold member 22 swung downward into horizontal position against the supporting stand 24, the bar 57 is moved laterally toward the side bar 30 until positioned so as to engage the associated

side margin of the matrix or mat to be now used. To permit of such adjustment of the bar 57, the set screws 58, 62, and 65 are first loosened. In Figs. 2 and 3, is shown a matrix or mat 69 having a bastard measure, that is, having substantially about one column and one-half in width and about one-half a column in length. When the mat 69 is applied beneath the clamping frame, one of the side margins of the mat is engaged by the side bar 30; the rear margin of the mat is engaged by the rear bar 32, and the innermost side margin of the mat is engaged by the adjustable bar 57. Should the bar 57 need additional lateral adjustment so that its inset or groove 66 will properly receive the bolster of the seat, in case the latter is provided with a bolster, such adjustment of said bar may be readily made by moving the bar laterally in the desired direction. After said bar 57 has been adjusted, the same is forced endwise against the rear bar 32 by the screw 58 and then clamped in its position of adjustment by the set screws 62 and 65. Then the movable mold member 22 is raised to close the mold box, and the two members thereof are clamped together by the clamps 23, 23. The molten stereotype metal in the pot 39 is then allowed to flow therefrom into the mold cavity and so effect the casting of a printing plate from said mat 69. As shown in said Figs. 1, 2, and 5, the adjustable bar 57 is provided adjacent its outer end with an overflow passage 70, which, when the mold box is closed, establishes communication between the chambers on each side of the adjustable bar 57. Consequently, when the level of the molten metal poured into the chamber containing the mat 69 reaches the passage 70, a continued pouring of such molten metal will cause an overflow thereof into the chamber on the opposite side of said bar 57. To prevent the overflow metal from surrounding and solidifying, when cold, about the adjustable rod 63, I place in the chamber above the same a slug 71, which, as shown in Fig. 2, extends across the chamber between the bar 57 and the side bar 31. Said slug 71 is made of a material to which the stereotype metal will not adhere, and I provide several of such slugs 71, each being of a length to extend between the bars for every adjustment of the bar 57. It is to be of course understood that the slug 71 is placed in position before the mold box is closed. The pot 39 is located at the side of the casting box 20 adjacent the side bar 30, so that the pot may discharge its molten metal into the mold cavity regardless of how narrow it may be formed by the adjustment of the bar 57. After a printing plate has been cast from the mat 69, the casting box 20 is opened and the casting printing plate removed, whereupon the poured end or tail of the metal above the upper edge of the mat is

sawed or cut off. When it is desired to cast a printing plate of dimensions less or greater than defined by the mat 69, another mat of the required size is placed in the mold box, the clamping bar 57 adjusted in accordance therewith, and the operations described above repeated.

The height of the casting box is such that there is a blank portion of metal on the printing plate between the top of the mat used and the upper edge of the casting box. It is necessary to saw or cut off such portion of metal before the printing plate is ready for use. In other words, the poured or tail end of the cast printing plate must be cut or sawed off, as is apparent. This is true whether the cast printing plate has the full dimensions of the casting box or of a size defined by the mat 69, as shown in Figs. 2 and 3. To eliminate as much of such sawing as possible, and require the cutting off of only a minimum amount of metal at the poured end of the printing plate, I employ the following means. As shown in Figs. 2, 3, and 7, I extend into the mold chamber in which the mat 69 is located, a rod 72, having at its inner end a flat slug 73 made of brass or other suitable material to which the stereotype metal will not adhere. Said rod 72 extends through a sleeve 74, and is clamped therein by a set screw 75. Said sleeve is provided with a hook 76 adapted to engage over the slotted bar 33, for the purpose of attaching said rod 72 to said slotted bar. Said slug 73 has detachable connection with the associated end of said rod 72, and, as shown in Fig. 7, such connection comprises a split stud 77 on the end of the rod, adapted to extend into and engage a hole or aperture 78 in said slug. By such means, the rod 72 may be readily withdrawn from said slug 73. Any other suitable form of connection may be provided in order to accomplish the purposes desired. With respect to the parts just referred to, I will describe their use in connection with the matrix or mat 69. As shown in Figs. 2 and 3, the slug 73 is flat and relatively narrow, that is, it has a width or height slightly less than the distance between the mat and the opposed flat face of the stationary mold member 22, as shown in Figs. 3 and 7. Said slug 73 has a length so as to extend from the adjustable bar 57 to a point terminating short of the side bar 30, thus leaving sufficient space between the end of the slug and side bar 30 to permit the molten stereotype metal to be poured into the portion of the mold chamber occupied by the mat 69. While the casting box 20 is open and the movable mold member 22 is down, the rod 72 is placed so that the slug 73 at its inner end rests upright with its now lower longitudinal margin on the upper edge of the mat 69 along the outer edge of the bolster thereof, and with one side edges of

said slug bearing endwise against the adjacent side face of the adjustable clamping bar 57. The sleeve 74 is adjusted endwise of said rod 72 until its hook 76 engages over 5 the outer edge of the slotted bar 33, whereupon the sleeve is clamped to the bar 72 by the set screw 75. The mold box 20 is then closed and the molten metal poured to effect the casting of a printing plate from the mat 10 in the mold chamber. The pouring of the molten metal is continued, as hereinbefore described, and such metal flows around the slug 73 and its bar 72, as clearly shown in Fig. 8. In said figure, I have shown a 15 printing plate 79 cast from said mat 69, and it will be noted that the poured end or tail 80 of the metal extends about the bar 72, and above the slug 73. In said Fig. 8, I have shown, for the sake of clearness of 20 illustration, said printing plate 79 removed from the mold box 20, but in practice said printing plate at such time is still hot and soft and in the mold box. While still in the closed mold box and before said plate 79 25 becomes chilled and solidified sufficiently to permit its removal from said mold box, the rod 72 is withdrawn from the box, leaving the slug 73 in the plate, as shown in Fig. 10. After said rod 72 has been withdrawn, 30 and the printing plate 79 cast has chilled and become solidified, the mold box is opened and the plate removed, whereupon the slug 73 is removed, leaving a slot 81 in said plate. Said slot 81 extends partially 35 across the plate 79 from one side thereof, and opens upwardly throughout its length through the printing face thereof. This is due to the fact that the slug 73 bears edge-wise against the operative face of the mat, 40 as shown in Figs. 3 and 7. As the opposite edge of the slug terminates short of the flat face of the stationary mold member 22, as shown in said figures, there is a portion of metal between the bottom wall of the slot 45 81 and the back of the printing plate, as shown in Figs. 8 to 10. After the slug 73 has been removed from the plate 79, the poured end or tail 80 thereof is struck a blow sufficient to effect the cracking of the plate 50 along the bottom of the slot 81. As shown in Fig. 10, such line of severance 82 extends the full length of said slot 81. Then the portion of the plate 79 between the closed end of the slot 81 and the adjacent side edge 55 of the plate is sawed or cut substantially along the dotted line 83, as shown in Fig. 10. Then the part of the plate 79 containing the type characters is ready for use in a press. By the means described, it is apparent that 60 it becomes necessary to saw or cut off but a minimum amount of the poured end or tail of a printing plate. In case the printing plate to be cast has a width less or greater than the one referred to, the slug 73 used 65 will of course have a length accordingly.

When the matrix or mat is provided with bolsters 68, as shown in Figs. 12 and 13, said bolsters project into the associated grooves or insets 66 in the bars of the clamping frame 29. As illustrated in Fig. 12, the 70 bolster 68 is of such width as to completely fill the groove 66 and, in addition, project laterally slightly beyond the same, while, in Fig. 13, I have shown a bolster 68 of such width failing to completely fill the 75 groove 66, whereas, in Fig. 11, I have shown a mat 84 of the type devoid of a bolster. When the molten stereotype metal is poured into the mold chamber against a mat provided with a bolster 68, the latter prevents 80 the marginal portion of the metal immediately surrounding the printing face of the plate being cast from contacting with the colder metal clamping bars 30, 32, and 57. Thus, such portion of the metal printing 85 plate being in contact with paper or like material of which the mat is made will not in chilling and solidifying shrink or contract to such an extent as to cause the distortion or complete elimination of those 90 type characters being cast along the outer boundary of the printing face, as would happen in case the colder clamping bars were devoid of the grooves 66 and had their edges in direct contact with the mat about 95 such marginal portion. Then again, said bolsters cause the edges of the printing plate surrounding the printing surface to be lower than the same, and thus prevent the necessity of beveling or trimming the same 100 before the cast plate is ready for use in a press. In case the mat is devoid of bolsters, as shown in Fig. 11, the molten metal flows into and fills the insets or grooves 66, thus again compensating for the shrinkage 105 of the metal and preventing a distortion or complete elimination of the marginal type characters above referred to.

When casting a printing plate having the full dimensions of the mold box 20, it is 110 advisable to core the back of the same, so as to eliminate as much metal as possible and further effect a reduction of the total weight of the plate when cast. To accomplish this purpose, I employ a core plate 85, 115 as shown in Figs. 14 to 17. Said core plate 85 is made of a relatively thin, flat sheet of brass or any other suitable metal and of such dimensions as to substantially cover the flat front face of the stationary mold member 120 21 when placed flatwise against the same. Said core plate 85 is suspended from the upper edge of said stationary mold member 21 by means of hooks 86, 86, the latter being secured to the upper edge of said plate. 125 On the front face of said plate 85, I place a plurality of outwardly projecting core pieces 87, 87, the latter being secured to said plate by a plurality of fastening screws 88, inserted through the back of the 130

plate into said core pieces. The heads of said screws are flush with the back of the core plate, so that the latter will bear flatwise through its length and width against the front flat face of the stationary mold member. Said core pieces 87 are vertically arranged and are laterally spaced apart, and have the cross-sectional shape as best shown in Fig. 16, so as to readily pull out of the printing plate when cast. Each core piece 87 is provided along its length with a plurality of transversely extending kerfs or slots 89, 89, which permit the formation of strengthening webs being formed on the back of the cast printing plate and extending across the cored portions thereof. Said core plate 85 is clamped against the front face of the stationary mold member 21 by the bars of the clamping frame 29, and the core pieces 87 are made of such width and spaced laterally apart to such an extent as not to hinder the clamping bar 57 being adjusted laterally for casting printing plates having standard newspaper measures, such as one, two, three, or more columns wide. The thickness of the core plate 85 is such, and the hinge connection of the movable mold member 22 has sufficient play as to enable a type-high printing plate to be cast, with or without said core plate. When casting a printing plate having a bastard measure, such as one-half a column or two columns and a half wide, the core plate 85 is not used. Cuts of pictures, cartoons, special sized advertising spaces, and special features, such as comic strips, are, as a general rule, of a bastard measure. With the mat 69, the core plate could not be used.

My machine is particularly designed for use by printers of rural newspapers and the like. The matrices or mats are supplied from a common mat-making and news-furnishing source. The matrices are light in weight and easily handled, and the transportation cost from the maker to the user is reduced to the minimum, when compared with a service where the printing plates themselves are sent from the maker to the user. With my machine, the stereotype metal used one day for a job is melted over for the job the next day. Furthermore, the machine having means permitting the casting of type-high printing plates of various lengths and widths, the rural newspaper can print anything the big metropolitan dailies can, such as cartoons, features, pictures, and the special sized ads of the big metropolitan stores.

It is to be of course understood that the casting machine or apparatus herein described and shown in detail may be variously modified and changed as to its details of construction, without departing from the spirit and scope of my invention, and I do

not wish to be limited to the exact details of construction and arrangement of parts shown, except as pointed out in the annexed claims.

I claim as my invention:

1. A device for casting stereotype printing plates, comprising a casting box, embracing a pair of mold members, one being moved toward and from the other in the opening and closing of said casting box; there being a mold chamber formed between said mold members when the casting box is closed, a clamping frame pivotally secured to one of said mold members and adapted to hold a matrix or mat in said mold chamber, said frame comprising two side bars, an inner end bar forming the bottom wall of said mold chamber when the casting box is closed, an adjustable bar interposed between and arranged substantially parallel to said side bars, and clamping means adapted to hold said adjustable bar in any position of its lateral adjustment for permitting the casting of printing plates of various widths.

2. A device for casting stereotype printing plates, comprising a casting box, embracing a pair of mold members, one being moved toward and from the other in the opening and closing of said casting box; there being a mold chamber formed between said mold members when the casting box is closed, a clamping frame pivotally secured to one of said mold members and adapted to hold a matrix or mat in said mold chamber, said frame comprising two side bars, an inner end bar, an outer end bar, an adjustable bar interposed between and arranged substantially parallel to said side bars and engaging said inner end bar, and means connecting said adjustable bar with one of said side bars and the outer end bar, for enabling said adjustable bar to be adjusted laterally and thereby permit the casting of printing plates of various widths.

3. A device for casting stereotype printing plates, comprising a casting box, embracing a pair of mold members, one being moved toward and from the other in the opening and closing of said casting box; there being a mold chamber formed between said mold members when the casting box is closed, a clamping frame pivotally secured to one of said mold members and adapted to hold a matrix or mat in said mold chamber, said frame comprising two side bars, an inner end bar, an outer end bar, the latter being provided with an elongated slot, an adjustable bar interposed between and arranged substantially parallel to said side bars and engaging said inner end bar, and a clamping member extending through said slot and connected with said adjustable bar for holding the latter in any position of its lateral adjustment.

4. A device for casting stereotype print-

ing plates, comprising a casting box, embracing a pair of mold members, one being moved toward and from the other in the opening and closing of said casting box; there being a mold chamber formed between said mold members when the casting box is closed, a clamping frame pivotally secured to one of said mold members and adapted to hold a matrix or mat in said mold chamber, said frame comprising two side bars, an inner end bar, an outer end bar, the latter being provided with an elongated slot, an adjustable bar interposed between and arranged substantially parallel to said side bars and bearing endwise against said inner end bar, a clamping member extending through said slot and connected with said adjustable bar for holding the latter in any position of its lateral adjustment, and means adapted to move said adjustable bar endwise against said inner end bar.

5. A device for casting stereotype printing plates, comprising a casting box, embracing a pair of mold members, one being moved toward and from the other in the opening and closing of said casting box; there being a mold chamber formed between said mold members when the casting box is closed, a clamping frame pivotally secured to one of said mold members and adapted to hold a matrix or mat in said mold chamber, said frame comprising two side bars, an inner end bar, an outer end bar, the latter being provided with an elongated slot, an adjustable bar interposed between and arranged substantially parallel to said side bars and bearing endwise against said inner end bar, a set screw engaged with said adjustable bar and adapted to move the same endwise against said inner end bar, and a clamping member extending through said slot and connected with said set screw.

6. A device for casting stereotype printing plates, comprising a casting box, embracing a pair of mold members, one being moved toward and from the other in the opening and closing of said casting box; there being a mold chamber formed between said mold members when the casting box is closed, and a clamping frame pivotally secured to one of said mold members and adapted to hold a matrix or mat in said mold chamber, said frame including two side bars, an inner end bar, an adjustable bar interposed between and arranged substantially parallel to said side bars and bearing endwise against said inner end bar, means for moving said adjustable bar endwise against said inner end bar, and means for permitting said adjustable bar to be moved laterally for permitting the casting of printing plates of various widths and holding said adjustable bar in any position of its endwise and lateral adjustments.

65 7. A device for casting stereotype print-

ing plates, comprising a casting box, embracing a pair of mold members, one being moved toward and from the other in the opening and closing of said casting box; there being a mold chamber formed between said mold members when the casting box is closed, and a clamping frame pivotally secured to one of said mold members and adapted to hold a matrix or mat in said mold chamber, said frame comprising two side bars, an inner end bar, an outer end bar, the latter being provided with an elongated slot, an adjustable bar interposed between and arranged substantially parallel to said side bars and bearing endwise against said inner end bar, a clamping member extending through said slot and connected with said adjustable bar for holding the latter in any position of its lateral adjustment, a rod connected with and extending laterally from said adjustable bar through one of said side bars, and fastening means for clamping said rod in any position of its endwise adjustment.

8. A device for casting stereotype printing plates, a supporting stand, a casting box mounted on said stand, said casting box embracing a pair of mold members, one being stationary and arranged upright, and the other having hinged connection with said stand and adapted to be moved toward and from said stationary mold member in the opening and closing of said casting box; there being a mold chamber formed between said mold members when the casting box is closed; the mouth of said mold chamber being formed at the upper edge of said casting box, a melting pot supported above said casting box and having a discharge spout extending into the mouth of said mold chamber, and a valve member mounted on said melting pot and adapted to control the flow of molten metal from said pot into said mold chamber.

9. A device for casting stereotype printing plates, comprising a supporting stand; a casting box mounted thereon and embracing a stationary mold member and a movable mold member, said stationary mold member being arranged upright on said stand, and said movable mold member being hinged to said stand and adapted to be moved toward and from said stationary mold member in the opening and closing of said casting box; there being a mold chamber formed between said mold members, when the casting box is closed; the mouth of said mold chamber being at the upper edge of said casting box, a melting pot secured to said stand and being arranged above the upper edge of said casting box, said pot being provided with a discharge spout extending into the mouth of said mold chamber, a vertically arranged valve member slidably supported in said pot and adapted to control the flow of molten

metal from the latter into said mold chamber, and a handle for raising and lowering said valve member.

10. A device for casting stereotype printing plates, comprising a supporting stand, a casting box mounted thereon and embracing a stationary mold member and a movable mold member, said stationary mold member being arranged upright on said stand, and 10 said movable mold member being hinged to said stand and adapted to be moved toward and from said stationary mold member in the opening and closing of said casting box; there being a mold chamber formed between 15 said mold members, when the casting box is closed; the mouth of said mold chamber being at the upper edge of said casting box, a melting pot secured to said stand and being arranged above the upper edge of said 20 casting box, said pot being provided with a discharge spout extending into the mouth of said mold chamber, a vertically arranged valve member slidably and rotatably supported in said pot and adapted to control 25 the flow of molten metal from the latter into said mold chamber, and a handle for raising and lowering said valve member.

11. A device for casting stereotype printing plates, comprising a supporting stand, a casting box mounted thereon and embracing a stationary mold member and a movable mold member, said stationary mold member being arranged upright on said stand, and said movable mold member being hinged to 30 said stand and adapted to be moved toward and from said stationary mold member in the opening and closing of said casting box; there being a mold chamber formed between said mold members, when the casting box is 35 closed; the mouth of said mold chamber being at the upper edge of said casting box, a melting pot secured to said stand and arranged above said casting box, said pot being provided with a discharge spout extending 40 into the mouth of said mold chamber, a vertically arranged valve member slidably and rotatably supported in said pot and adapted to control the flow of molten metal 45 from the latter into said mold chamber, a standard secured to said pot and extending 50 above the same, a handle lever pivoted at one end to said standard, said valve member extending loosely through said lever between the ends thereof, and stop members on said 55 valve member, said stop members being arranged adjacent to and one on each side of said lever.

12. A device for casting stereotype printing plates, comprising a supporting stand, a casting box mounted thereon and embracing a stationary mold member and a movable mold member, said stationary mold member being arranged upright on said stand, and said movable mold member being hinged to 60 said stand and adapted to be moved toward

and from said stationary mold member in the opening and closing of said casting box; there being a mold chamber formed between said mold members, when the casting box is closed; the mouth of said mold chamber being at the upper edge of said casting box, a melting pot secured to said stand and being arranged above the upper edge of said casting box, said pot being provided with a discharge spout extending into the mouth of 70 said mold chamber, a vertically arranged valve member slidably supported in said pot and adapted to control the flow of molten metal from the latter into said mold chamber, a handle for raising and lowering said valve member, and a heat retaining casing surrounding the side walls of said pot.

13. A device for casting stereotype printing plates, comprising a casting box, embracing two mold members, one being moved toward and from the other in the opening and closing of said casting box; there being a mold chamber formed between said mold members when the casting box is closed, and a clamping frame adapted to hold a matrix 85 or mat in said mold chamber, said frame consisting of two side bars, an end bar constituting the bottom wall of the mold chamber when the casting box is closed, and an adjustable bar interposed between and arranged substantially parallel to said side bars, one of said side bars, the end bar, and said adjustable bar each being provided, along its edge immediately adjacent the boundary of the type-casting face of the 90 mat, with a longitudinally extending inset or groove adapted to receive the bolster of the mat and thereby prevent the type characters cast around the boundary of the mat from being eliminated or distorted by the 95 shrinkage of the stereotype metal poured into the mold chamber.

14. A device for casting stereotype printing plates, comprising a casting box, embracing two mold members, one being moved 110 toward and from the other in the opening and closing of said casting box; there being a mold chamber formed between said mold members when the casting box is closed, a clamping frame for holding a matrix or mat 115 in said mold chamber and comprising bars, which form the side and bottom walls of the mold chamber when the casting box is closed, a slug adapted to be placed in said mold chamber immediately beyond the upper edge of the casting face of the mat and to extend from one of the side walls of the mold chamber to a point short of the opposite side wall thereof, and means for holding said slug in said mold chamber during the 120 casting of a printing plate therein.

15. A device for casting stereotype printing plates, comprising a casting box, embracing two mold members, one being moved toward and from the other in the 130

opening and closing of said casting box; there being a mold chamber formed between said mold members when the casting box is closed, a clamping frame for holding a matrix or mat in said mold chamber and comprising two side bars and an inner end bar, a flat slug adapted to be placed in said mold chamber immediately beyond the upper edge of the casting face of a mat and to extend from one of said side bars to a point short of the opposite side bar, a rod detachably connected with said slug, and means removably holding said rod in said mold chamber.

16. A device for casting stereotype printing plates, comprising a casting box, embracing two mold members, one being moved toward and from the other in the opening and closing of said casting box; there being a mold chamber formed between said mold members when the casting box is closed, a clamping frame for holding a matrix or mat in said mold chamber and comprising two side bars, an inner end bar, and an outer end bar, a flat slug adapted to be placed in said mold chamber immediately beyond the upper edge of the casting face of a mat and to extend from one of said side bars to a point short of the opposite side bar, a rod detachably connected with said slug, and a member connected with said rod and adapted to detachably engage said outer end bar for removably holding said rod in said mold chamber.

17. A device for casting stereotype printing plates, comprising a casting box, embracing two mold members, one being moved toward and from the other in the opening and closing of said casting box; there being a mold chamber formed between said mold members when the casting box is closed, a clamping frame for holding a matrix or mat in said mold chamber and comprising two side bars, an inner end bar, and an outer end bar, a flat slug adapted to be placed in said mold chamber immediately beyond the upper edge of the casting face of said mat and to extend from one of said side bars to a point short of the opposite side bar, a rod detachably connected with said slug, a sleeve slidably mounted on said rod, a set screw adapted to clamp said sleeve and rod together, and a hook-shaped member connected with said sleeve and adapted to engage over said outer end bar for removably holding said rod in said mold chamber.

18. A device for casting stereotype printing plates, comprising a casting box, embracing two mold members, one being moved toward and from the other in the opening and closing of the casting box; there being a mold chamber formed between said mold members when the casting box is closed, a plate adapted to be placed in said mold chamber and against one of said mold

members, means for detachably connecting said plate with said mold member, core pieces, and means for securing said core pieces to said plate; the means for securing said core pieces to said plate being independent of the means for detachably securing said plate to one of said mold members.

19. A device for casting stereotype printing plates, comprising a casting box, embracing two mold members, one being moved toward and from the other in the opening and closing of said casting box; there being a mold chamber formed between said mold members when the casting box is closed, a clamping frame for holding a matrix or mat in said mold chamber, and means for partially severing the poured end of the metal immediately beyond the upper edge of the casting face of the mat during the casting operation.

20. A device for casting stereotype printing plates, comprising a casting box having a mold chamber therein, a clamping frame adapted to hold a matrix or mat in said mold chamber, said frame embracing side bars, and an inner end bar, one of said side bars being adjustable laterally to permit the casting of printing plates of various widths, means adapted to clamp said adjustable bar in any position of its lateral adjustment, and means adapted to move said adjustable side bar endwise against said inner end bar.

21. A device for casting stereotype printing plates, comprising an upright casting box having a mold chamber therein and with the mouth of said mold chamber being formed at the upper end of said casting box, a melting pot supported above said casting box and having a discharge spout extending into the mouth of said mold chamber, and a valve member mounted on said pot and adapted to control the flow of molten metal from said pot into said mold chamber.

22. A device for casting stereotype printing plates, comprising a casting box, embracing two mold chambers, one being moved toward and from the other in the opening and closing of the casting box; there being a mold chamber formed between said mold members when the casting box is closed, a plate adapted to be placed in said mold chamber and against one of said mold members, said plate being provided with hooks for detachable engagement with said mold member, and core pieces provided on said plate.

23. A device for casting stereotype printing plates, comprising a casting box, embracing two mold members, one being moved toward the other in the opening and closing of said casting box; there being a mold chamber formed between said mold

- members when the casting box is closed, a clamping frame adapted to hold a matrix or mat in said mold chamber, said frame comprising two side bars, an inner end bar, and 5 an adjustable bar interposed between and arranged substantially parallel to said side bars, and said adjustable bar being provided adjacent one end with an overflow opening.
- 10 24. A device for casting stereotype printing plates, comprising a casting box, embracing two mold members adapted to be moved one toward the other in the opening and closing of said casting box, and a 15 clamp member adapted to clamp said mold members together when the casting box is closed, said clamp member being pivoted on one of said mold members and being provided with a part adapted to bear against said mold member, so that such pivot means 20 will be relieved of the strains exerted on the clamp member when the latter clamps said mold members together.
- In testimony that I claim the foregoing as my invention, I affix my signature in 25 the presence of two witnesses, this 22nd day of June, A. D. 1917.

PATRICK A. TOOMEY.
